STEPHEN PARISH, OF STEUBENVILLE, OHIO.

REVERSING-VALVE FOR GAS-FURNACES.

1,267,898.

Specification of Letters Patent.

Patented May 28, 1918.

Application filed August 17, 1917. Serial No. 186,739.

To all whom it may concern:

Be it known that I, STEPHEN PARISH, a citizen of the United States of America, and resident of Steubenville, county of Jefferson, and State of Ohio, have invented certain new and useful Improvements in Reversing-Valves for Gas-Furnaces, of which the following is a specification.

This invention relates broadly to reversing valves for furnaces, and more particularly to an improved reversing-valve of the butterfly type.

The primary object of the invention is to provide a reversing-valve for gas furnaces having automatically actuated means for protecting the ends of the butterfly valve from the warping effect of the intense heat of the products of combustion which are directed thereagainst.

A further object is to provide means for effectively sealing the joints at that end of a valve of the character mentioned which is most liable to become warped by intense heat, so that gas passing from the generator into the furnace will not escape into the stack.

A still further object is to provide a valve of the character mentioned having a casing which can be cast in sections and the latter bolted together instead of being cast in one piece, thus not only simplifying manufacture but also providing for ready access to all parts of the structure.

With these and other objects in view, the invention resides in the features of construction, combination of elements and arrangement of parts which will hereinafter be fully described, reference being had to the accompanying drawings, in which—

Figure 1 is a side elevation of a reversing-valve for gas furnaces embodying my invention;

Fig. 2 is a longitudinal section of the same; and—

Fig. 3 is a transverse section taken substantially on the line 3—3, Fig. 2.

Referring to said drawings, in which like designating characters distinguish like parts throughout the several views—

1 indicates a box-like middle casing section which is open at both ends, flanges 2 and 3 being provided around the end openings thereof. Said flanges have bolted thereto similar flanges 4 and 5 of two similar end casing sections 6 and 7 which are in open communication through their lower

sides with the opposite sides of a gas furnace (not shown).

The end sections 6 and 7 are provided with suitably located ports or manholes 8 and 9 through which access to their interiors may be had when occasion requires. Said ports are normally closed by removable heads 10 and 11.

Formed integral with or rigidly attached to the middle casing section 1 at its topmost portion is a tubular neck portion 12 affording a passage 13 through which gas passes from a generator (not shown) to the interior of casing section 1. An outlet port 14 is provided at the bottom of said section 1 through which the products of combustion may pass to a stack (not shown).

A shaft 15 extends transversely across the center of the middle casing section 1 and has attached thereto interiorly of said section a butterfly-valve 16 which extends completely across the interior of said section. Said valve is designed to divide the interior of said section 1 into two separate passageways when at its limits of movement, one passageway connecting the source of fuel supply with one side of the furnace and the other connecting the other side of the furnace with the stack.

Formed in the casing section 1 at opposite sides of the inlet passage 13 are recesses 17 and 18 in which the upper end 16^a of the butterfly valve 16 seats when the latter occupies its limits of movement, shoulders 19 and 20 protecting said upper end of said valve from the heat and the resultant warping effect of the products of combustion issuing from the interior of the furnace.

Mounted upon the interior walls of the casing section 1 are stop-blocks or abutments 21 and 22 against which the sides of the valve 16 seat when occupying positions at the limits of movement of said valve.

The lower end 16^b of the valve 16 lies closely adjacent to interior tongues 23 and 24 projecting upward from the lowermost interior wall of the casing section 1. Mounted on trunnions 25 and 26 rotatably received within the interior side walls of said section 1 and having their pivoted edges disposed closely against the tongues 23 and 24, are oppositely disposed valve-like shields or wings 27 and 28 adapted to have their free edges seat against the adjacent face of valve 16 when said valve occupies a

position at one of its extremities of movement, and adapted to have their free edges swing downward to an out-of-the-way position when not in operation, as clearly shown in Fig. 2. Said wings effectually shield the lower end of the valve 16 from the heat and the resultant warping effect of the intensely heated products of combustion passing from the interior of the furnace to the stack, and, due to the close fit between the wings and the tongues and valve, also prevent gas passing from the generator to the furnace from escaping into the passage leading to the stack.

One end of the shaft 15 extends outward through the walls of casing section 1 and has rigidly mounted thereon a crank 29 of substantially inverted Y-shape, said crank being fastened to said shaft at the junction of its arms. Pivoted to the outer end of the main arm of said crank is a rod or pitman 30 which leads to a suitable location and constitutes means whereby movement of said lever, for shifting valve 16, is accomplished.

The ends of trunnions 25 and 26 extend outward through the side wall of casing section 1 and carry thereon crank arms 31 and 32 the outer ends of which are connected to the divergent arms 29^a and 29^b of crank 29, as by chains 33 and 34. The chains are of such length, and the cranks 31 and 32 are so disposed on their trunnions with respect to wings 27 and 28 that when valve 16 is swung to one of its limits of movement the free end of the wing adjacent to its lower edge is forcibly drawn upward tightly thereagainst and the opposite wing is permitted to swing to an out-of-the-way position.

When the movable parts occupy the positions shown in full lines in Fig. 2, gas from the generator enters the interior of casing section 1 through inlet passage 13 and passes thence downward through an end section into one side of the furnace; and, at the same time, the products of combustion issuing from the opposite side of the furnace pass upward into and through the opposite end section and into the interior of casing 1, where they are diverted downward through outlet port 14 by the butterfly valve 16 and thence to the stack. As is obvious, when the movable parts occupy the positions shown in dotted lines in said figure, the direction of travel of gas through the furnace is reversed.

What is claimed is—

1. A reversing-valve for gas furnaces comprising a casing having inlet and outlet ports therein and having passages leading to opposite sides of the furnace, a butterfly-valve rotatably disposed within said casing and designed to divide the interior thereof into two separate continuous pas-

sages, recesses formed in the interior of said casing for receiving the upper end of said valve, means for shielding the lower end of said valve from contact with the products of combustion passing through said casing, a substantially Y-shaped crank associated with said valve for rotating the latter, and means associated with the divergent arms of said crank for actuating said valve-shielding means. 75

2. A reversing-valve for gas furnaces comprising a casing having inlet and outlet ports therein and having passages leading to opposite sides of the furnace, a butterfly-valve rotatably disposed within said casing and designed to divide the interior thereof into two separate continuous passages, wings pivoted in said casing and designed to shield the lower end of said valve from the warping effect of products of combustion issuing thereby, means for operating said valve, and means associated with said valve-operating means whereby said valve-shielding means are automatically actuated. 80

3. A reversing-valve for gas furnaces comprising a casing having inlet and outlet ports therein and having passages leading to opposite sides of the furnace, a butterfly-valve rotatably disposed within said casing and designed to divide the interior thereof into two separate continuous passages, recesses formed in the interior of said casing for receiving the upper end of said valve, wings pivoted in said casing and designed to shield the lower end of said valve from the warping effect of products of combustion issuing thereby, means for operating said valve, and means associated with said valve-operating means whereby said valve-shielding means are automatically actuated. 85 90

4. A reversing-valve for gas furnaces comprising a casing having inlet and outlet ports therein and having passages leading to opposite sides of the furnace, a rotatable shaft directed transversely through the center of said casing, a butterfly-valve fixed on said shaft within said casing and designed to divide the interior thereof into two separate continuous passages, recesses formed in the interior of said casing for receiving the upper end of said valve, wings having integral trunnions received in opposite sides of said casing and on which said wings are rotatable, said wings being designed, when in one position, to protect the lower end of said valve from contact with heated products of combustion, a crank mounted upon one extremity of said shaft whereby said valve may be shifted, said crank having a pair of divergent arms, and means connecting said arms with said trunnions whereby said wings are operated. 100 105 110

5. A reversing-valve for gas furnaces comprising a casing having inlet and outlet ports 115 120 125 130

therein and having passages leading to opposite sides of the furnace, a rotatable shaft directed transversely through the center of said casing, a butterfly-valve fixed on said shaft within said casing and designed to divide the interior thereof into two separate continuous passages, recesses formed in the interior of said casing for receiving the upper end of said valve, wings having integral trunnions received in opposite sides of said casing and on which said wings are rotatable, said wings being designed, when in one position, to protect the lower ends of said valve from contact with heated products of combustion, a crank mounted upon one extremity of said shaft whereby said valve may be shifted, said crank having a pair of divergent arms, cranks fixed to the outer ends of said trunnions, and chains connecting the extremities of the last-mentioned cranks with the extremities of the divergent arms of said first-mentioned crank.

6. A reversing-valve for gas furnaces comprising a casing having inlet and outlet ports therein and having passages leading to opposite sides of the furnace, a rotatable shaft directed transversely through the center of said casing, a butterfly-valve fixed on said shaft within said casing and designed to divide the interior thereof into two separate continuous passages, recesses formed in the interior of said casing for receiving the upper end of said valve, wings having integral trunnions received in opposite sides of said casing and on which said wings are rotatable, said wings being designed, when in one position, to protect the lower ends of said valve from contact with heated products of combustion, a crank mounted upon one extremity of said shaft whereby said valve may be shifted, said crank having a pair of divergent arms, cranks fixed to the outer ends of said trunnions, and chains connecting the extremities of the last-mentioned cranks with the extremities of the divergent arms of said first-mentioned crank, said

chains being of such length and said last-mentioned cranks being so disposed with respect to said wings that when said valve occupies one of its limits of movement the free end of the wing adjacent to the lower edge of the former is forcibly drawn upward against said valve.

7. A reversing-valve for gas furnaces comprising a casing having inlet and outlet ports therein and having passages leading to opposite sides of the furnace, a rotatable shaft directed transversely through the center of said casing, a butterfly-valve fixed on said shaft within said casing and designed to divide the interior thereof into two separate continuous passages, recesses formed in the interior of said casing for receiving the upper end of said valve, wings having integral trunnions received in opposite sides of said casing and on which said wings are rotatable, said wings being designed, when in one position, to protect the lower ends of said valve from contact with heated products of combustion, a crank mounted upon one extremity of said shaft whereby said valve may be shifted, said crank having a pair of divergent arms, cranks fixed to the outer ends of said trunnions, and chains connecting the extremities of the last-mentioned cranks with the extremities of the divergent arms of said first-mentioned crank, said chains being of such length and said last-mentioned cranks being so disposed with respect to said wings that when said valve occupies one of its limits of movement the free end of the wing adjacent to the lower edge of the former is forcibly drawn upward against said valve and the opposite wing is permitted to swing to an out-of-the-way position.

In testimony whereof, I affix my signature in presence of two subscribing witnesses.

STEPHEN PARISH.
